UNITED STATES PATENT OFFICE.

JOSIAH H. WILLIAMS, OF BALTIMORE, MARYLAND.

INHALATION DEVICE.

1,387,030.

Specification of Letters Patent.

Patented Aug. 9, 1921.

Application filed August 6, 1919. Serial No. 315,678.

To all whom it may concern:

Be it known that I, JOSIAH H. WILLIAMS, a citizen of the United States, residing at Baltimore, in the county of Baltimore city 5 and State of Maryland, have invented new and useful Improvements in Inhalation Devices, of which the following is a specification.

This invention relates to a device for use 10 in the treatment of affections or diseases of the respiratory organs by inhalation of medicinal substances.

The primary object of the invention is to provide a device which may be supported 15 upon the chest of a recumbent or sleeping patient whereby the healing vapors emanating from a volatile medicament may be directed toward the mouth and nostrils of the patient, so that at all times during the respiration 20 of the patient the air inspired will be impregnated with the healing agent.

A further object is to provide a device of the character described which is simple, inexpensive and efficient in construction and 25 which may be compactly packed for sale and storage in transportation or when not in use.

The invention consists of the features of construction, combination and arrangement of parts, hereinafter fully described and 30 claimed, reference being had to the accompanying drawing, in which:—

Figure 1 is a view illustrating the mode of use of the device.

Fig. 2 is a vertical longitudinal section of 35 the device as set up for use.

Fig. 3 is a perspective view of the distending frame removed from the bag or sack.

Fig. 4 is a front view of the bag or sack 40 with the frame removed therefrom.

Fig. 5 is a detail section showing the securing tab as used for holding the frame in collapsed condition.

Fig. 6 is a perspective view of the sponge cup.

Fig. 7 is a top plan view of the inhalation 45 device.

In carrying my invention into practice I provide an inhalation device comprising a receptacle 1 of somewhat greater length 50 than width and of suitable form and size to rest upon the chest of a recumbent patient, as shown in Fig. 1. This receptacle may be made of any suitable material or combination of materials, and includes a bottom wall 55 or layer 2, a top wall or layer composed of a central portion 3 and end portions 4, and

front walls 5. As shown, the bottom wall or layer 2 is composed of an oblong rectangular strip of flexible material adapted to lie in close contact with the chest and conform 60 to the contour thereof, while the wall portions 2, 3, 4 and 5 are also made of flexible material capable of assuming the form shown when the receptacle is distended and of folding so as to permit the receptacle to 65 collapse in substantially flat form when not held distended, so that it may be conveniently stored when not in use and packed in compact shape in a box or like container for sale or transmission through the mails. 70

The top wall, composed of the portions 3 and 4, may be made, like the bottom 2, of a single strip of material, and the front walls 5 may be integral therewith, it being only necessary that the component parts described be adapted to perform the designed functions and to assume the shape disclosed when the receptacle is distended for use. For reasons hereinafter stated, I preferably make the bottom 2 of a soft, absorbent material, such as canton flannel, which is sufficiently porous to permit the animal heat to pass from the chest of the patient into the receptacle, and which will also permit vapors generated by such heat to pass into 85 the receptacle, in cases where the medicament is applied directly to the chest of the patient. The wall portions 3, 4 and 5, on the contrary, are preferably made of rubberized cloth or other suitable impermeable 80 flexible material adapted to prevent direct upward escape of the heat and vapors and to confine the same within the receptacle for discharge only through the outlet 6 thereof. 90

The receptacle is designed to be held when in use in a distended position by means of an expandible and collapsible or foldable frame 7. This frame is of a length equal to the width of the receptacle, but is of restricted width relative to the length of the 100 receptacle, being of a width substantially equal to that of the outlet 6 and of the central portion 3 of the top wall. This frame is substantially V-shaped and comprises bottom and top walls or members 8 and 9 connected by spring hinges 10 at the rear or vertex portion of the frame, said hinges serving to hold the frame members open or spread, as shown in Fig. 3, and adapting them to be closed or folded in parallel relation. The frame is fitted in the central portion 105 of the receptacle 1 with the vertex por-

tion thereof bearing against the line of fold between the wall portions 2 and 3, and with the members 8 and 9 lying in contact with said wall portions, as shown in Fig. 2. 5 Hence when the members 8 and 9 are free for spreading motion, the wall portions 3 and 4 (the portion 3 directly and the portion 4 indirectly) will be elevated thus holding the receptacle 1 distended. 10 In practice the frame 7 may be tacked by stitches at suitable points to the receptacle 1, if it should be desired to have it permanently secured therein, or it may be loosely fitted in position so that it may be removed 15 for greater convenience in cleansing the receptacle when occasion requires. The frame is shown as made of wire or reticulated material, but may be made of other suitable material, it being only essential to have the 20 lower member 8 perforate so that the animal heat (and vapors under certain conditions) rising from the breast of the patient may pass upward into the receptacle. For the purpose of holding the frame and 25 receptacle collapsed, a fastening device is provided comprising a flexible tab 11 attached at one end to the front cross bar of the member 9, said tab carrying spring stud and socket members 12 and 13. When the 30 frame is folded, this tab, as shown in Fig. 5, may be passed around the front cross bar of the frame member 8 and the stud and socket engaged to hold the frame in folded condition. The receptacle will thereby be 35 held flat, so that it may be compactly stored, when not in use or packed in a box for storage or mail shipment. At each front corner of the frame member 8 is a strap 14, of suitable material, one end of which is fastened 40 to the frame and provided with a buckle 15 to which the free end of the strap may be fastened. These straps are designed to be looped about the shoulders of the patient, as shown in Fig. 1, so that the inhaler 45 may be held in operative position for use and prevented from becoming displaced by the body movement of the wearer or by shifting of the bed clothing. It is obvious that the spring hinges 10 may be strong 50 enough to hold the wall 3 elevated and the receptacle 1 distended under the weight of the bed clothing, which may thus be drawn close up about the patient and over the receptacle, so as to protect the patient from 55 drafts without interfering with the use of the inhaling device.

It will be evident that the weight of the frame 7 will hold the central part of the bottom layer 2 in close contact with the center of 60 the chest of the patient, allowing the ends of said layer to assume the curvature of the sides of the chest and lie in close contact therewith. This is of importance in collecting the body heat of the patient and 65 transmitting the same to the interior of the

receptacle when vapors are to be generated in said receptacle and such vapors kept in a vaporous state. Close contact of the layer 2 with the chest is also of importance when a medicament containing a vaporizable substance or substances is applied directly to the chest or to the layer 2. The medicament used may be a salve consisting of a petroleum base containing the volatile crystals of 70 essential oils or healing agents, or it may be 75 in the form of a vaporizable liquid. In the case of a salve, the medicament may be applied to the chest or to the absorbent strip 2, and in the case of a liquid a suitable cup 16 for the reception of a sponge 17 and a desired quantity of the liquid may be used and 80 may be held by spring clips 18 on the member 8. In either case the healing agents will be volatilized by the heat from the body and the vapors therefrom will be received in the 85 receptacle 1 and discharged through the outlet 6 for use.

It will be observed that, as the bottom and top strips of the receptacle 1 are directly joined at their outer longitudinal edges and 90 connected at their front edges—on opposite sides of the outlet 6—by the triangular walls 5, the upward pressure of the frame member 9 will spread said top and bottom walls mainly at the center. As a result the central portion 3 of the top wall will be inclined or sloped upwardly and forwardly to a major extent and the end portions 4 of the top walls similarly inclined to a less extent, while said portions 4 will be inclined 95 or sloped also in an upward and inward direction toward the central portion 3 of the top wall. Hence the portions 3 and 4 will 100 act as deflectors guiding the ascending vapors toward the central front outlet 6. Thus 105 while a receptacle of ample size to receive an adequate quantity of vapor at all times is produced, all the vapor may be discharged through a relatively small outlet and thereby concentrated and emitted in such close 110 proximity to the mouth and nostrils of the patient that the surrounding atmospheric air inspired by the patient will be densely impregnated with the vapors. By reference to Fig. 1 it will be seen that the device will 115 be supported on the chest of the wearer sufficiently close to the mouth and nostrils to saturate the inspired air with the vapor, but not so close as to prevent the patient from 120 breathing in a requisite amount of air. Normal respiration will, therefore, be permitted and waste of vapors prevented, while the air inspired will be impregnated with just the right proportion of healing vapor to 125 give the proper therapeutic effect. The walls 3, 4 and 5 being made of impermeable material it will be obvious that no escape of vapor can take place therethrough, and accordingly all the vapor will discharge 130 through the outlet 6. In the collapsing of

the receptacle 1 the walls 5 fold accordion-fashion so as to secure compactness.

In order to guide the vapors from the outlet 6 close to the mouth and nostrils of a patient whose head is supported in a low position, a vizor-like front deflector 19 may be provided. This reflector 19 is provided with depending side walls 20 abutting against the walls 5, and said deflector is provided with a central tongue 21 which may be slidably fitted between the frame member 9 and top wall portion 3, whereby the deflector is detachably held in position. The deflector may be made of the same material as the top wall and will guide the vapor sufficiently close to the mouth and nostrils to insure its inspiration with the air. The deflector may be removed when it is desired to collapse the device for storage. If desired, the tongue 21 may be provided with a slot or opening for passage of a spring stud 22 on the top 3 for additional security in making use of the tab 11 to hold the deflector in position.

The device will be found of great value in treating irritations or diseases of the respiratory tract, in that by its use a medicated vapor may be supplied within the zone of respiration of the patient for inspiration with the air, whereby the inspired air will be impregnated with the healing vapor and the vapor carried therewith into the most remote portions of the respiratory tract. By its use also the treatment may be carried on during the night as well as the day, so that a constant supply of the healing vapor to the seat of the trouble may be furnished. It will be found of special value in relieving irritation and allaying coughs liable to disturb the sleep of the patient, thereby enabling the patient to obtain a refreshing sleep, as well as to obtain the value of carrying the medicated vapor to the extreme portions of the lungs during sleep when the inspirations are deepest. It will be understood from the foregoing that the device may not only be used for supplying medicated vapor without local chest treatment, but may also be employed for the double purpose of utilizing the vapor from a medicament applied directly to the chest so that the value of internal as well as external treatment may be simultaneously obtained. Other advantages of the invention will be apparent from the foregoing description.

Having thus fully described my invention, I claim:

1. An inhalation device comprising a receptacle formed of flexible material, said receptacle having top and bottom walls longitudinally joined at their rear edges and connected by folding side walls at their front edges, said side walls being spaced to provide an intervening outlet, and a frame adapted to fit within the central portion of

said receptacle to hold the top and bottom walls thereof spread in line with said outlet.

2. An inhalation device comprising a flexible receptacle having a central outlet in a side thereof and having a porous base and an impermeable top, a removable frame fitted within the central portion of said receptacle for holding the bottom and top portions spread in line with the outlet, and means carried on said frame for holding a supply of a suitable volatile medicament.

3. An inhalation device comprising a flexible receptacle having an outlet, and a frame composed of spring-pressed top and bottom members fitted in said receptacle for holding the top and bottom walls thereof spread, the bottom member of said frame being composed of perforate material.

4. An inhalation device comprising a flexible receptacle having an outlet, a frame composed of spring spread members removably fitted within said receptacle for holding the top and bottom walls thereof spread, means removably supported on said frame for holding a supply of a suitable volatile medicament, and means for holding the members of said frame in collapsed condition.

5. An inhalation device comprising a receptacle formed to provide sloping top wall portions and a bottom wall and having an opening through the side wall thereof, said receptacle being flexible to adapt the same to the chest portion of a human body, said top wall portions being formed of an impermeable material and its bottom wall of a permeable material, and adapted to receive and confine vapor from a suitable volatile medicament, and means for directing the vapor toward the mouth and nostrils of the person.

6. An inhalation device comprising a receptacle formed to provide sloping top wall portions and a bottom wall and having an opening through the side wall thereof, said receptacle being flexible to adapt the same to the chest portion of a human body, said top wall portions being formed of an impermeable material and its bottom wall of a permeable material and adapted to receive and confine vapor from a suitable volatile medicament, means for directing the vapor toward the mouth and nostrils of the person, and means for holding said receptacle distended.

7. An inhalation device comprising a receptacle formed to provide sloping top wall portions and a bottom wall and having an opening through the side wall thereof, said receptacle being adapted to rest upon the chest portion of a human body, said top wall portions being formed of a flexible impermeable material and its bottom wall of a flexible permeable material, and adapted to receive and confine vapor from a suit-

able volatile medicament, means for directing the vapor toward the mouth and nostrils of the person, and means for holding said receptacle distended.

5 8. An inhalation device comprising a collapsible receptacle formed to provide sloping top wall portions and a bottom wall and having an opening through the side wall thereof, said top wall portions being formed of a 10 flexible impermeable material and its bottom wall of a flexible permeable material, said receptacle being adapted to receive and confine vapor from a suitable volatile medicament, said bottom wall being adapted to contact the body of the person whereby the heat from the latter is transmitted to the interior of the receptacle, means for directing the heated vapor toward the mouth and nostrils of the person, and means for holding said receptacle distended.

9. An inhalation device comprising a collapsible receptacle formed to provide sloping top wall portions and a bottom wall and having an opening through the side wall thereof, said top wall portions being formed of a flexible impermeable material and its bottom wall of a flexible permeable material, means within said receptacle for holding a supply of a suitable volatile medicament, 25 said bottom wall of said receptacle being adapted to contact the body of the person whereby the heat from the latter is trans-

mitted to the interior of said receptacle, means for directing the vapor from said heated medicament toward the mouth and nostrils of the person, and means for holding said receptacle distended.

10. An inhalation device comprising a collapsible receptacle formed to provide top wall portions and a bottom wall, the central 40 of said top wall portions sloping rearwardly and connecting an intermediate portion of the rear edge of said bottom wall, the oppositely disposed of said top wall portions sloping outwardly and rearwardly from said central top wall portion and connecting the rear edge and end edge portions of said bottom wall, spaced front wall portions connecting the front edge portions of the oppositely disposed portions of said top wall 45 portions and the front edge of said bottom wall, the space between said front wall portions forming an opening at the front of the receptacle, means for holding said receptacle distended, means for securing the receptacle 50 in position on the chest portion of the human body, means within said receptacle for holding a supply of a suitable volatile medicament, and means extending from the opening between said front wall portions for directing vapor from said medicament toward the mouth and nostrils of a person.

In testimony whereof I affix my signature.
JOSIAH H. WILLIAMS.
